[57] CLAIM

The ornamental design for a slicer for food, as shown and described.

DESCRIPTION

FIG. 1 is a front and left side perspective view of a slicer for food according to our new design;

FIG. 2 is a back and right side perspective view of the slicer for food of FIG. 1, with the base removed for ease of illustration;

FIG. 3 is identical to FIG. 2, but with the base installed;

FIG. 4 is a back and left side perspective view of the slicer for food of FIG. 1, with the base installed; and,

FIG. 5 is a top plan view of the slicer for food of FIG. 1. The bottom plan view is plain and unornamented.
